(57) **CLAIM**

We claim the ornamental design for a compartmented container with tear strips for storing and dispensing multiple rolls of wrapping paper, as shown and described.

DESCRIPTION

FIG. 1 is a perspective view of a compartmented container with tear strips for storing and dispensing multiple rolls of wrapping paper showing our new design with one end cap removed for purposes of clarity; the broken lines depict environmental structure for illustrative purposes only and form no part of the claimed design;

FIG. 2 is a side elevational view thereof, the elevational view of the opposing side being identical thereto;

FIG. 3 is an end elevational view thereof, the elevational view of the opposing end being identical thereto; and,

FIG. 4 is a top plan view thereof, the bottom plan view being identical thereto.
